UNITED STATES PATENT OFFICE.

RICHARD MAX EATON, OF NIAGARA FALLS, NEW YORK.

PORTABLE-LAMP APPARATUS.

994,094.

Specification of Letters Patent.

Patented May 30, 1911.

Application filed July 21, 1910. Serial No. 572,985.

To all whom it may concern:

Be it known that I, RICHARD MAX EATON, a citizen of the United States, residing at Niagara Falls, in the State of New York, have invented certain new and useful Improvements in Portable-Lamp Apparatus; and I do hereby declare the following to be a full, clear, and exact description of the invention, such as will enable others skilled 10 in the art to which it appertains to make and use the same.

This invention relates to improvements in apparatus for portable lamps, which may be carried by firemen, policemen and people in 15 like occupations, my object being to produce an electric lamp, the battery for which is carried upon the person.

My invention will be best understood by reference to the following description when 20 taken in connection with the accompanying illustration showing specific embodiments thereof, while its scope will be more particularly pointed out in the appended claims.

Figure 1 shows the apparatus mounted 25 upon the person of a fireman. Fig. 2 is a modified form showing a lamp adapted to be carried in the hand. Fig. 3 shows the lamp and mounting means. Fig. 4 shows a battery case. Fig. 5 is an elevation of a battery 30 adapted to be used therewith. Fig. 6 is the cross-section of the battery. Figs. 7 and 8 illustrate a plug and socket for connecting the light wires.

Referring now to the figures of the drawing and the embodiment of the invention shown therein, 1 and 2 are clamping springs adapted to fit around the brow of a person and furnish a mounting means for the lamp, when the same is worn upon the head as 40 shown in Fig. 1.

3 is a pillow pivoted at 4 to the mounting means.

7 is a lamp mounted upon one end of 3.

5 is the reflector and 6 a glass or wire 45 screen cover therefor, serving to protect the lamp where it is used in smoke or gas filled places.

8 and 9 are the conductors or leads, which are connected to the lamp and to a plug 50 socket 10. The plug socket is adapted to cooperate with a plug 13, to make a circuit connection.

At 11 I show a belt worn about the person. This belt passes through loops 11' 55 upon a battery case 12.

Conducting leads 14' and 15' are connected

to the plug 13 and terminate in terminal connectors 14 and 15. These connectors are adapted to be folded over the edge of the case 12, so that they project down on the 60 inside thereof.

At 16 I show a battery, preferably, a storage battery, which is adapted to be slipped into the case 12. On one end of this battery are terminals 17 and 18, which are connected to the electrodes of the battery and which engage the terminal connectors 14 and 15 when a battery is slipped into the case.

At 19 I show a ventilator for the battery and at 20 a handle for convenience in changing the batteries in the case. The battery contains a false end 21 and is sealed by means of a sealing compound shown at 22.

In the form shown in Fig. 2, I show a handle 30 connected to the reflector 5, so that 75 the lamp may be carried in the hand.

In the form shown in Fig. 3, the part 3, carrying the lamp may be turned upon the pivot 4 to elevate or depress the light according to the desire.

The members 1 and 2 are sprung apart and a part of the body upon which the lamp is to be worn, is inserted therein and the springs allowed to grip the same, holding the lamp in position. The battery case 85 is also mounted upon any suitable part of the body, such for example, as the belt, as shown. A battery is slipped into the case and the plug and plug socket connected, completing the circuit of the lamp. The 90 fireman or other person using the lamp is then free to use his hands for other purposes. The lamp will be unaffected by smoke or gases, such as are generated in ordinary fires.

While I have shown these particular forms 95 of my invention, it will be obvious to those skilled in the art that numerous and extensive departures from the forms and details of the apparatus here shown, may be made without departing from the spirit of 100 this invention, the same being herein shown, solely for the purpose of clearly illustrating specific embodiments thereof.

I claim—

1. In a device of the class described, the 105 combination of lamp mounting means consisting of two flexible springs adapted to grip the side of the head or hat of a person, an upright post pivoted to said springs and adapted to swing in a vertical plane upon 110 said pivot, a lamp mounted at the upper end of said post, a source of energy to supply en-

ergy to said lamp adapted to be carried on the body and means to transmit energy from said source to said lamp.

2. In a device of the class described, the combination of a pair of flexible springs connected together at one end and adapted to grip the side of the head or hat and to adhere thereto, a supporting member pivoted to said springs where they are fastened together and adapted to swing upon said pivot in a vertical plane, a lamp mounted upon said member, a source of energy carried upon the person for supplying energy to said lamp and means to connect said source to said lamp.

3. In a device of the class described, the combination of a pair of flexible springs integral with each other and adapted to grip the sides of the head or hat of a person,

said springs being bent into a loop where they are joined, a post pivoted in said loop in a position substantially perpendicular to the plane of the long axis of the springs, and adapted to swing in a plane perpendicular to the plane of its pivot, the upper end of said post being enlarged, a lamp socket mounted in said enlarged portion, the open end of the socket being on the side of the post opposite to the springs, a lamp mounted in said socket, a reflector therefor, a source of electric current and conductors for connecting said source to said lamp.

In testimony whereof, I affix my signature in the presence of two witnesses.

RICHARD MAX EATON.
